UNITED STATES PATENT OFFICE

FRANK WOLF, OF NEW YORK, N. Y.

ACCESSORY FOR CONTAINERS

Application filed December 24, 1928. Serial No. 328,101.

This invention relates to an improved accessory for containers, particularly collapsible tubes for putting up and vending shaving cream and various other preparations, such as compounds for use in the care of the teeth.

An object of the invention is to provide an attachment or accessory which can be conveniently secured directly to and removed from the tube; and, when in place on the tube, utilized in various ways to support the tube, mount a cap for the outlet end of the tube, and for other purposes.

Collapsible tubes usually have a cone-shaped comparatively rigid top, the outer periphery of which forms a stiff bead or flange united with the body of the tube; the body being more or less yielding so that the tube can be squeezed to expel the contents. The top with the flange is stronger and more rigid; and I utilize this feature in the practice of my invention by so designing the parts of the attachment that the top of the tube is engaged and the body of the tube adjacent to the bead or flange is gripped, and even pressed inward somewhat, so that the attachment is securely held in place by clamping the tube at the point where the flange is disposed. Preferably the engagement is effected at diametrically opposite points on the tube.

Other objects and advantages of the invention will be fully set forth in the following description, taken with the accompanying drawings, which show several forms in which the invention is embodied; and I reserve the right to make changes, not illustrated, but nevertheless within the principle and scope of the invention, as indicated by the broad meaning of the terms in which the appended claims are expressed.

On the drawings,

Figure 1 shows a side view of one form of the invention;

Figures 2 and 3 are side views seen from the right and left, respectively, of what appears on Figure 1;

Figure 4 is a side view of another form;

Figures 5 and 6 are side views seen from the right and left, respectively, of what appears on Figure 4;

Figure 7 is a view partly in section showing a further modification;

Figure 8 is a view seen from the right of what is shown in Figure 7;

Figures 9 and 10 are diagrammatic views, illustrating the operation of the accessory when it engages the container;

Figure 11 is a side view of a further modification;

Figure 12 is a side view, partly in section, of what appears in Figure 11; and

Figure 13 is a plan view of what is shown in Figure 12.

On the drawings the same numerals identify the same parts throughout.

The soft body of the collapsible tube is shown at 1, with a relatively stiff and rigid conical top 2 terminating at its upper end in a threaded outlet neck 3, which is closed in ordinary tubes by the usual screw cap. 70 Around the periphery of the top, which is the lower end thereof when the tube is upright, is a bead or flange 4. The attachment or accessory comprises a member 5, which in Figures 1, 2 and 3, has the form of a cover shaped similar to the top 2 and fitting thereon. This cover may have a depending rim 6. The rim 6 has an extension 7, with two spring arms 8, projecting from the sides of the extension and lying parallel to the length of the tube. The ends of the arms are received in recesses 9 in the rim 6, and have external, transverse projections 10. On the extension 7 is a central bearing 11 pivotally mounting a catch 12. This catch is curved, providing two arms, and has a handle 13. The catch might be made out of a piece of strong wire bent upon itself. By lifting the handle 13 and depressing it, the two arms of the catch 12 can be swung downward or moved up to 90 press inward on the arms 8. When the catch is up as far as the projections 10 allow, the catch forces the ends of the arms 8 against the tube 1 just below the bead flange 4 of the latter. Thus the member 5 is held in place. 95 It can be taken off by releasing the catch 12, and lowering the arms of the catch to remove the pressure on the arms 8.

The upper ends of the arms 8 may be pressed against the bead 4, and just below the 100

upper ends may have projections 8a to press into the body 1, immediately below the flange 4.

Figures 4, 5 and 6 show an accessory in the form of a conical ring 14 to fit upon the cone-shaped top 2 of the tube around the lower outer edge 4 thereof and to this ring may be pivoted a similar catch 12a. On the member 14 are spring fingers 16, depending from the ring 14 and the two arms of the catch pass under these fingers to hold the attachment on, and grip the soft sides of the tube 1 below the top 2. This attachment may carry an eyelet or hook 15 to enable the tube to be hung up when not in use.

Of course in the forms shown in Figures 1, 2, 3, 4, 5 and 6, there may be two catches 12 or 12a, one at each side of the tube, if desired.

The member 5 of Figures 1, 2 and 3 may serve for various purposes such as to provide the tube with a hook or the like to hang it up, as in the form shown in Figures 4, 5 and 6; or carry an arm 17 hinged at 18, bearing a closure 20, with a gasket 21; and this arm 17 may have a handle 19 to move the arm 17 and closure thereon.

In Figures 7 and 8 I show an attachment in the form of a member or cover 5a having projections 22 which are turned downward and then outward at 23. These projections are located at opposite sides of the tube and are adapted to engage beneath the flange 4 and press inward against the exterior surface of the tube 1 at opposite points on the circumference of the tube. The neck 3 projects through the member 5a, and a rubber washer or gasket 24 may be between the top 2 and the upper end of the member 5. The projections 22 are of course stiff, but elastic and springy. When the member 5a is put on the tube, it is forced downward upon the top 2, and the projections 22 pass over the bead-flange 4, and then spring inward towards the tube just below the flange 4, gripping the soft body 1. This form may also have the cap 20 or the like, the same as in the form shown in Figures 1, 2 and 3.

The mode in which the tube 1 is gripped to hold the member 5, 14 or 5a in place is illustrated fully on Figures 9 and 10. Figure 9 shows an ordinary tube, and in Figure 10 the numeral 25 indicates a depression at the point where the part 22, for instance, makes contact with the tube. This part forces the soft side of the tube inward just under the bead-flange 4, and takes a firm grip on the outside of the tube. In the form shown in Figures 7 and 8, the gripping engagement is at opposite sides of the tube, where the fingers 22 are located; and the same gripping engagement at opposite points is given in the form shown in Figures 1, 2 and 3, by way of the arms 8. In the modification of Figures 4, 5 and 6 the gripping is done directly by the

catch 12a pressing inward against the side of the tube 1 under the flange 4, over the entire length of the catch 12a. Thus the member is held firmly on, and the top of the tube is strengthened and made more durable in handling so that it preserves its shape longer and only the soft body 1 is collapsed and deformed when the contents of the tube are squeezed out.

In Figures 11, 12 and 13, the member 5b has a rim 6b, and this rim is interrupted to make room for a pair of resilient fingers 16, as in Figures 4, 5 and 6, extending downward from the edge of the member 5b. The rim 6b has a bearing 11b for a catch 12b, and between the bearing 11b and the fingers 16 the rim is recessed at 26 to give clearance to the two arms of the catch. On the member 5b is a neck 27 to fit over the neck 3.

To put on this attachment the screw cap 85 which is bought with the tube is removed and then the cover member 5b is fitted upon the conical top 2 of the tube 1 with the neck 27 enveloping this neck 3. The rim 6b extends downward past the bead-flange 4 90 around the top 2 of the tube and when the handle 13b of the catch is depressed to move the catch from broken-line or to full-line position in Figure 11 the arms of the catch 12b pass behind the fingers 16 and part of 95 the rim, up against the flange 4 of the top and hold the accessory fast.

The attachment in all the forms disclosed herein thus engages the tube directly at the sides under the flange 4 where the material of the tube is soft and affords a positive gripping engagement so that the attachment is securely held in place.

The construction illustrated in Figures 11, 12 and 13 is fully disclosed in my copending application Serial No. 247,499, for accessory devices for collapsible tubes, filed January 18, 1928, of which this case is in part a continuation.

On the member 5b is a closure cap 28, mounted on a spring hinge 29, which tends to raise the cap. It is held down by a catch 30 on the member 5b engaging a stop 31 on the cap 28.

I claim:

1. An accessory for a collapsible tube having a soft body and a comparatively rigid top, with a bead-flange around its periphery, the accessory comprising a member to fit upon the top, strengthening it and preserving its shape, the member having projections extending down past the bead-flange, a catch pivoted on said member and comprising a pair of arms curved to extend around the tube, and a handle on said catch to enable said arms to be forced under said projections against the side of the tube to hold the member in place.

2. An accessory for attachment to a collapsible tube having a soft body and a com- 130

paratively rigid top with a bead-flange surrounding the periphery of the top, the accessory comprising a member to fit upon the top in contact therewith and strengthen the latter to maintain its shape, the member having a rim portion to engage the upper surface of the bead-flange, an extension on the rim portion extending transversely of the circumference of the bead-flange, spring-arms on the extension to be disposed on opposite sides of said tube, transverse projections on the outer faces of said arms, the rim portion having recesses to receive the ends of said arms, and a catch pivoted on the extension comprising a pair of curved arms and a handle therefor to swing the curved arms into engagement with the spring arms and force the ends of the spring arms against the opposite sides of the tube under the bead-flange and opposite the rim portion to grip and retain the bead-flange between the rim portion and the spring arms.

3. An accessory for a collapsible tube having a soft body and a comparatively rigid top with a bead-flange around the periphery of the top, the accessory comprising a member shaped to fit upon the top to strengthen and protect the top, and spring projections on the member extending down over the bead-flange and inward, said projections being yieldable so that when the member is forced on the top of the tube the projections will give until the ends are past the bead-flange and will then engage securely with the sides of the tube below the member to hold the member in place.

4. An accessory for a collapsible tube having a soft body and a comparatively rigid top with a bead-flange around its periphery, the accessory comprising a member adapted to be placed upon the rigid top and including a rim portion to contact with the upper surface of the bead-flange, a part carried by said member at a point opposite to said rim portion to engage the underside of the bead-flange and bind it to the rim portion, said part being adapted to press into the soft body and complete the binding effect, and mechanical means carried by said member whereby to manipulate said part.

5. In combination with a collapsible tube having a soft body and a comparatively rigid conical top with a stiff bead-flange around its periphery outstanding from the body, a conical member shaped to fit upon the top and having a rim portion overlying the upper surface of the bead-flange, projections on said rim portion formed to extend across the bead-flange and to engage the underside thereof so as to bind the bead-flange to the rim portion and hence to hold the conical top to the conical member, said projections being yieldable with respect to the rim portion and adapted to be forced into the soft body inwardly beyond the bead-flange to thereby

further bind the bead-flange and prevent disengagement thereof, and means in connection with the rim portion for forcing said projections inwardly into the soft body.

In testimony that I claim the foregoing as my invention, I have signed my name hereto.

FRANK WOLF.
